UNITED STATES PATENT OFFICE.

WILLIAM C. HEDGCOCK, OF CHICAGO, ILLINOIS, ASSIGNOR TO AMERICAN STEEL
FOUNDRIES, OF CHICAGO, ILLINOIS, A CORPORATION OF NEW JERSEY.

REVERSIBLE FULCRUM.

Application filed August 13, 1921. Serial No. 492,030.

To all whom it may concern:

Be it known that I, WILLIAM C. HEDGCOCK, a citizen of the United States, residing at Chicago, in the county of Cook and State 5 of Illinois, have invented certain new and useful Improvements in Reversible Fulcrums, of which the following is a specification.

This invention relates to brake beams and 10 more particularly to reversible fulcrums forming a part thereof.

One object of the invention is to provide a simple and efficient reversible fulcrum for brake beams which will satisfactorily answer the requirements for a fulcrum which may be used right-hand or left-hand and at 15 the same time prevent the existence of lost motion longitudinally of the fulcrum body and properly perform its function as a strut 20 of the brake beam truss.

A further object is to provide a multi-piece reversible fulcrum which may be made in part or entirely by forging and in which the parts cooperate to meet all the requirements of service conditions.

These and other objects are accomplished by means of the arrangement disclosed on the accompanying sheet of drawings, in which—

30 Figure 1 is a fragmentary top plan view of a brake beam embodying my invention;

Figure 2 is a side elevation of the same showing the tension and compression members in section;

35 Figure 3 is a sectional view taken in the plane of line 3—3 of Figure 2 showing means for limiting reversible movements of the fulcrum body;

Figure 4 is a sectional view taken along 40 the plane of the same line 3—3 of Figure 2 and showing the fulcrum body in one of its limiting positions;

Figures 5, 6 and 7 are fragmentary top plan views of a brake beam showing modified means for attaching the fulcrum body to the compression member;

Figure 8 is a fragmentary side elevation 45 of a fulcrum body showing modified means for connecting the fulcrum body to an associated saddle member; and

Figures 9 and 10 are fragmentary top plan views of other modifications showing connections between the fulcrum body and tension member of the brake beam.

The various novel features of the invention will be apparent from the following description and drawings and will be particularly pointed out in the appended claims.

Referring to the figures of the drawings, it will be noted that I have disclosed my invention in connection with a truss type of 60 brake beam including a compression member 10, a tension member 11 and fulcrum 12 extending therebetween.

Referring particularly to Figures 1 and 2 of the drawings, it will be noted that the fulcrum includes a main body portion 13 having spaced arms 14 between which a 65 brake lever, not shown, may be pivotally mounted. The rear end of these arms 70 14 are integrally connected by a cross-piece 15 from which extends an integral projection 16. This projection extends through an opening 17 in the web 18 of the compression member 10 and is upset 75 to form a head 19. The opposite sides of the web 18 of the compression member are clamped between the cross-piece 15 and the head 19 for preventing any lost motion 80 between the compression member and fulcrum longitudinally of the latter, and for yieldably holding the reversible fulcrum in its different adjusted positions. Sufficient play, however, is provided between the walls of the opening 17 and the projection 16 to prevent any binding action.

This main body portion of the fulcrum preferably is forged so that it may be easily reformed in the event that it becomes distorted and may take a standard form while 90 various types of tension rod saddles may be secured thereto. In the arrangement shown in Figures 1 and 2 the tension rod saddle 20 is provided with an opening 21 in alignment with an opening 22 in the forward 95 part of the fulcrum body 13, a rivet 23 being passed through said openings and having the heads 24 and 25 at the opposite ends thereof for clamping together the fulcrum body 13 and saddle 20 for assisting in maintaining the fulcrum bracket in its adjusted position and eliminating any lost motion 100 between the parts longitudinally of the fulcrum body. There is sufficient clearance between the walls of the openings 21 and 22 and the rivet 23 to prevent any binding therebetween.

To limit the reversible movements of the

fulcrum body 13 the cross-piece 15 is provided with angular extension portions 26 which engage the flanges 27 and 28 of the compression member, as shown particularly 5 in Figure 4.

If it is desired to have a slightly freer rotation between the fulcrum body and compression member the same may be accomplished by providing a washer 29 between the cross-piece member 15 and the web 18 of the compression member, as shown 10 in Figure 5 of the drawings. The same result may be accomplished by providing a washer 30 between the web 18 and the head 15 19, as shown in Figure 6. In both instances the washer is mounted over the projection 16.

In Figure 7 a separate rivet 31 is shown to pivotally connect the web 18 of the compression member and the fulcrum body 13.

20 Following out the arrangement shown in Figures 5 and 6, a washer 32 may be provided on the rivet 23, as shown in Fig. 8, engaging either the tension rod saddle or the fulcrum body for making rotation of the 25 fulcrum body a little freer than otherwise would be the case.

In Figure 9 a modification is shown in which the front end of the fulcrum body 13 is provided with an integrally formed 30 projection 33 which extends into a pocket 34 formed in the tension rod saddle 35, there being no riveting of parts, as shown in the other figures of the drawings. The converse arrangement is shown in Figure 10, 35 in which a tension rod saddle 36 is provided with a projection 37 which extends through an opening 38 in the front end of the fulcrum body 13.

By means of the various arrangements 40 here shown the main fulcrum body, which is reversible and limited in its reversible movements, is clamped in a manner to prevent lost motion longitudinally of the fulcrum body and held in its various adjusted posi-

tions to meet the various requirements for 45 successful commercial use.

It is my intention to cover all modifications of the invention falling within the spirit and scope of the following claims.

I claim:

1. In a brake beam, the combination of 50 tension and compression members, a reversible fulcrum body automatically having pivotal relationship with both of said members, one of said pivotal connections including a projection integrally formed with said fulcrum body and extending through the compression member and having clamping engagement therewith for eliminating lost motion longitudinally of said fulcrum body. 55

2. In a brake beam, the combination of 60 tension and compression members, a reversible fulcrum body automatically having pivotal relationship with both of said members, one of said pivotal connections including a projection integrally formed with said 65 fulcrum body and extending through the compression member and having clamping engagement therewith for eliminating lost motion longitudinally of the fulcrum body, 70 and means for limiting reversible movements of the reversible fulcrum body.

3. In a brake beam, the combination of a 75 compression member, a tension member, a reversible fulcrum body automatically having a pivotal relationship with said compression and tension members, one end of the fulcrum body having an integrally formed pivotal pin extending through the compression member and cooperating with the latter 80 for eliminating lost motion longitudinally of said fulcrum body, and a washer associated with said pin for reducing the holding effect. 85

Signed at Chicago, Illinois, this 9th day of August, 1921.

WILLIAM C. HEDGCOCK.
